MECHANICAL TOY

Application filed March 21, 1925. Serial No. 17,162.

An object of the present invention is to provide a motor driven mechanical toy of pleasing appearance which may be manufactured with comparative economy, which will be rugged and durable in use and which, by virtue of the life-like movements of the figure toys which it includes, may prove entertaining and amusing. In its broader aspects, the invention is applicable to a toy which includes a single motor actuated figure or manikin, although it is more particularly applicable to devices of the character in which a plurality of toy figures are caused to simulate a plurality of different human movements and in which the movements of the several figures, while radically different from each other, are nevertheless synchronized or harmonized.

In accordance with a specific embodiment of the invention, I provide a figure toy which includes a box-like motor casing which may conveniently represent a piano. The motor is caused to actuate a manikin arranged exteriorly of the casing in such a manner that it will appear to be playing the piano. Preferably the motor simultaneously actuates a dancing figure. The manikin at the piano is caused to sway back and forth and move its hands across the key board while the dancing figure is caused to jump up and down, kick its feet and turn first in one direction and then in another, to simulate a dance or jig. The movements of the two figures while of a totally different nature and occurring at different timed intervals are nevertheless so synchronized that the figure at the piano appears to be swaying in accompaniment to the movement of the dancing figure.

The invention may be more fully understood from the following description in connection with the accompanying drawings wherein:

Figure 1 is a perspective view of the toy,

Figure 2 is a fragmentary perspective view of a rear corner of the housing showing the manually operated mechanism for controlling the spring motor.

Figure 3 is a disassembled detail view indicating the construction of the arms of the figure toys,

Figure 4 is a sectional view on the line 4—4 of Figure 1, showing the motor substantially in plan,

Figures 5 and 6 are transverse sectional views on the lines 5—5 and 6—6 respectively of Figure 4.

Reference character 10 indicates a box-like housing which forms the motor casing and which is preferably shaped and decorated in a manner to closely simulate a musical instrument, such for instance, as an upright piano, including a forwardly projecting shelf-like keyboard portion 10^a. Casing 10 is preferably formed from a thin bendable sheet metal blank, the sections of which are interlocked by tongues 11 in a manner which is conventional and well understood in the toy art. The dancing figure may be of conventional construction and dressed or ornamented in any suitable manner. This figure includes a hollow sheet metal body 12 preferably integral with a head portion 13 having pivoted arms 14 which carry a representation 15 of a musical instrument such as a banjo. The hands of the figure include staple element 15' integral therewith and passed through corresponding apertures in the banjo, in which they are pivotally supported so that while the arms pivot at the shoulders, the banjo has a pivoting movement at the hands. The banjo serves as a strut connecting the hands, thereby preventing shifting of the arms to a point where they can be disengaged from the shoulders. The figure includes depending freely swinging leg portions 16 preferably hinged at the knees so that as a vertical movement is imparted to the figure, the arms and legs will swing and the legs will bend both at the hip and knee.

The figure is mounted on the upwardly projecting outer end 19 of a horizontal actuating rod 17 projecting through a vertical slot 18 in the front of the motor casing 10. As seen in Fig. 2, the turned up rod end 19, receives a sleeve 20 integral with the body which serves to mount the body for substantially free horizontal swinging movement. The manner in which the rod 17 is rhythmically lifted to impart vertical movement to the manikin and cause it to simulate a dancer,

and the arms with the banjo to move obliquely, will be more fully hereinafter described.

The figure at the piano is preferably legless for purposes of simplicity of construction and includes a body portion 21 integral with a head portion 22 and mounting movable arms 23, which as best seen in Figure 3 include suitably bent strips of sheet metal having T shaped tongues 24 at their ends inserted in openings 25 in the shoulder portions 10 of the body. The body 21 carries at its lower front a sleeve or bracket 26 receiving the upwardly turned end 27 of an actuating shaft 28 which latter is journaled in the front wall of the motor casing and is otherwise supported as will be later described. Intermittent rotation of the actuating rod in opposite directions will, through the medium of the extension 27 and bracket 26, cause the body to oscillate in a vertical plane. Movement of 15 said body about the extension 27 as a pivot is prevented by the use of a guide rod 29 extending transversely through the lower portion of the body and having its ends upset and guided in vertical slots 30 in the side 20 walls of a squared bracket or stand 31 which rests upon the floor and is conveniently shaped to simulate a low backed chair. Slots 30 permit oscillation of the figure 31 in a vertical plane. The free ends of the arms 23 normally rest flat upon the key board portion 32 of the piano or motor casing and as the figure sways back and forth the hands move over the key board, the arms pivoting 25 at shoulder mounts 24, so that the figure closely simulates a piano player who is swaying or rocking to right and left as he plays.

It will be noted that the stool 31 with the legless figure 21 constitutes a sub-assembly 30 completed at the factory so that in packing and putting together the device for use, this subassembly can be handled as a single unit and no extra fastening operation is necessary, while in operation, the figure moves 45 relative to the stool as heretofore set forth.

The motor which is housed within the casing 10 and which serves to oscillate actuating shaft 28 and intermittently lift the actuating rod 17 is generally similar to the motor disclosed in my prior Patent No. 1,393,936 of October 18, 1921. In adapting the casing 10 for mounting the motor, I preferably extend a bearing plate 40 transversely of the casing intermediate its ends. This 50 bearing plate may be integral with a horizontal plate 41 at its upper edge which carries a depending cooperating plate 42 considerably shorter than the plate 41 and spaced therefrom a distance equal to the width of 55 plate 41. A drum shaft 43 has its ends journaled in the end wall 44 of the casing and in the bearing plate 40, and beyond the end of wall 42. Fixed to the end of the shaft exteriorly of the casing is a handle or key 60 45 for winding the motor. The end wall 44 is

indented at 44^a as shown, thereby hardening or stiffening the metal adjacent the bearing of shaft 43 so that said bearing will not readily wear through. A drum 46 loose on the shaft 43 carries a relatively large driving gear 47 at its inner end. Power is transmitted from the drum shaft 43 to the drum through the agency of a helical torsion spring 48 encircling the drum. Spring 48 has one end connected to the drum at 49 and its other end connected to a projecting lug 50 on a ratchet wheel 51 keyed to the drum shaft. 70

A driving shaft 52 and a parallel counter-shaft 53 are journaled in the plates 40, 42 in parallelism with the drum shaft. The teeth of the main driving gear 47 engage with the skeleton hub 54 of a gear 55 keyed to the driving shaft 52. The gear 55 actuates a train of speed increasing gears 56, 57, and 58 which have a fly wheel effect on the motor and tend to maintain the same running at a uniform speed. Gear 55 meshes with the skeleton hub 56^a of gear wheel 56 loose on the countershaft. Gear wheel 56 in turn meshes with the skeleton hub 57^a of gear wheel 57 loose on the drive shaft, and the latter gear drives gear 58 through the medium of its skeleton hub 58^a. The entire gear train 90 may be held against rotation during winding operation of the coiled spring by throwing a lever 59 into engagement with the teeth of the last gear wheel 58. This lever has an offset 60 pivoted in the motor casing 10 and a projecting operating end 61 which extends through a horizontal slot 62 in the end 44 of the motor casing closely adjacent the winding handle 45. Any suitable type of pawl mechanism may be associated with the ratchet wheel 51 to prevent retrograde movement of the drum shaft 43 under the influence 100 of the spring 48.

This pawl may be in the nature of a pivoted plate 63, carrying a pair of pawl arms 64, 65. Tilting of the arm 64 by one advancing tooth swings the arm 65 into position 110 to lock the succeeding tooth against retrograde movement while positive tilting of the arm 65 by one tooth moves the arm 64 into position to hold a preceding tooth against retrograde movement. This pawl movement permits me to check at approximately one half tooth intervals and to use a large toothed wheel, thereby obviating the necessity for either cutting fine teeth on the ratchet or permitting considerable back lash in the motor. 115

Actuating rod 17 and shaft 28 are both driven from the main drive shaft 52 of the motor. To accomplish this purpose drive shaft 52 is provided at one end with an extension in the nature of a crank 52', said crank working in a yoke 66 formed by turning under the rear offset end of the shaft 28. Shaft 28 has a supplemental bearing in a bracket 67 struck from the motor casing 125 and rotation of the crank 52' serves to alter- 130

nately rotate the shaft 28 in opposite directions through the agency of the yoke 66 which is alternately lifted and depressed by the crank.

5. Keyed to the opposite end of the driving shaft 52 is a collar 70 carrying a plurality of radially projecting lifting fingers 71 which are successively engageable with a collar 72 fixed upon a vertical extension 73 of the actuating bar 17. An offset 74 connects extension 73 with the horizontally disposed figure carrying end or rod 17. Downward movement of the vertical extension 73 is limited by the engagement of the offset portion 74 with the plate 41. The extension 73 is guided in said plate and in a bracket 75 turned over from the plate 42. Any desired arrangement of lifting arms may be employed but I have found desirable the illustrated arrangement of three arms arranged at 90° apart, since this arrangement effects a vertical reciprocation of the dancing figure three times while causing the seated figure to sway back and forth once, the effect is produced of the dancing figure executing a jig in time with the swaying piano player.

The operation of the device is readily understood. When winding up the motor the lever 61 is thrown into the position of Figure 2 thereby locking the gear wheel 58 and the remainder of the gear train of the motor against actuation. Handle 45 is turned to wind up the spring 48, the ratchet and pawl mechanism 51, 63 preventing the spring from uncoiling. The extent to which the spring may be wound may be limited by its gripping engagement with the drum 45 as successive twists reduce its diameter. After the motor has been wound sufficiently, the lever 61 is swung away from the position of Figure 4, releasing the gear train and permitting the spring to rotate the drum and consequently the gear 47 and the train of gears driven thereby. Rotation of the drive shaft 52 operates as above noted to cause side wise rocking movement of the seated figure 21 and intermittent vertical reciprocation of the figure 12. This last mentioned figure is so arranged that when the actuating bar 17 is dropped by any one of the lifting fingers 71, the feet of the figure will strike the ground and cause the legs to bend one way or the other. The figure is, of course, free to sway about its pivot 20 and a certain amount of such side wise motion is an incident of the continual dropping of the figure on its feet.

It will be evident that a motor construction, such as that above described, may be modified to produce various movements of toy figures actuated thereby. It will also be evident that the particular combination of dancing figures may be actuated in other ways than by the specific motor construction and operating means shown. Attention is par-

ticularly called to the fact that while the toy figures move in synchronism they do not necessarily move simultaneously. One figure may be at rest while the other is moving and vice versa. The preferred and illustrated embodiment of the invention shows the motor housed in a casing which represents an upright piano, but it will be obvious that the motor might be otherwise housed in accordance with the particular class of dancing and moving figures which were driven thereby and the particular movements which these figures were intended to simulate.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

The brake mechanism disclosed herein is claimed per se in my copending application Serial No. 732,518, filed August 16, 1924.

Having thus described my invention, what I claim as new and desire to secure by Letters Patent is:

1. A toy of the class described including a motor casing simulating a musical instrument including a key board, a spring motor housed within the casing, a figure seated at the instrument and mounted for movement in a vertical plane and means operated by the motor for imparting a swaying movement to the figure in simulation of one playing the instrument.

2. A toy of the class described including a motor casing simulating a piano, a toy figure seated at the piano and mounted for movement in a vertical plane and a transmission between the motor and the toy figure for causing the latter to sway in a vertical plane.

3. A device of the class described in claim 2 wherein the figure includes movable arms formed with hand portions resting on the key board of the piano and moved over the key board by the swaying of the figure.

4. A toy of the class described including a motor, a motor casing, a horizontal operating rod projecting through the casing, a jointed figure toy pivotally mounted for horizontal swinging movement on the outer end of the rod and operative connections between the rod and the motor for vertically reciprocating the rod to cause the figure to simulate a dancer.

5. A toy of the class described including a

motor casing simulating an upright piano, a motor housed within the casing, a toy figure seated at the piano and a toy figure standing adjacent the piano, operative connections from the motor for causing the seated figure to sway and simulate a piano player and the standing figure to vertically reciprocate and simulate a dancer, said figures having different periodicities of movement and operating rhythmically in synchronism with each other.

6. A toy of the class described including a motor casing simulating an upright piano, a motor housed within the casing, a toy figure seated at the piano and a toy figure standing adjacent the piano, operative connections from the motor for causing the seated figure to sway and simulate a piano player and the standing figure to vertically reciprocate and simulate a dancer, the swaying figure being operated at regularly timed intervals and the dancing figure being operated rhythmically at irregularly timed intervals.

7. A device of the class described in claim 6 wherein the standing figure is mounted for free swinging movement about a horizontal pivot.

8. A device of the class described in claim 6 and wherein the seated figure is mounted for oscillatory movement in a vertical plane and held against swinging movement in a horizontal plane.

9. A toy of the class described including a casing, a motor housed within the casing, said motor including a power shaft, a pair of toy figures arranged on the exterior of the casing, means operable from one end of the power shaft for imparting oscillating movement to one of the toy figures, means operable from the other end of the power shaft for imparting reciprocating movement to the other toy figure, said first mentioned means including a crank, integral with the power shaft, an operating shaft, rigidly connected to one of the figures and means engaged by the crank for intermittently rotating the shaft in opposite directions.

10. A toy of the class described including a casing, a motor housed within the casing, said motor including a power shaft, a pair of toy figures arranged on the exterior of the casing, means operable from one end of the power shaft for imparting oscillating movement to one of the toy figures, means operable from the other end of the power shaft for imparting reciprocating movement to the other toy figure, said last mentioned means including a plurality of radially disposed lifting fingers fixed to the power shaft, an operating rod connected to one of the toy figures, and means whereby the lifting fingers successively effect elevation of the operating rod.

11. A toy of the class described comprising a spring motor, a casing therefor having a

sheet metal end wall of relatively large area, said motor having a shaft extending through said end wall, said end wall having a flat indented area to provide a hardened or stiffened bearing for the shaft.

12. A mechanical toy of the class described, in combination, a stool, a legless figure coacting with said stool, a guide rod extending transversely across said figure and extending through slots in the sides of said stool, and slidable longitudinally of said slots to permit a swaying movement of the figure, and means on said figure adapted for connection with respect to an external motor by which the swaying movement is effected.

13. A toy of the class described including a casing simulating an upright piano, a motor housed within the casing, a toy figure on the exterior of the casing including hands resting upon the keyboard portion thereof, a shaft projecting through the casing and connected to the toy figure and operative connections to the motor for intermittently rotating the shaft in opposite directions to cause oscillation of the toy figure.

Signed at New York, in the county of New York and State of New York, this 20th day of March A. D. 1925.

SAMUEL BERGER.
